UNITED STATES PATENT OFFICE

1,996,606

REPULSION RELAY

Edgar H. Ayers, Schenectady, N. Y., assignor to
 General Electric Company, a corporation of
 New York

Application February 17, 1934, Serial No. 711,816

9 Claims. (Cl. 175—338)

My invention relates to electroresponsive devices, more particularly to repulsion relays, and has for an object the provision of a rugged, easily adjustable relay of this type.

5 In repulsion relays of the type described and claimed in an application entitled Repulsion relay, Serial No. 711,666 filed February 17, 1934, L. W. Thompson, and assigned to the same assignee as the present invention, the adjustment of the relay is accomplished by bending the bracket which supports the armature, and while the adjusting means of the Thompson device is entirely operative something is yet to be desired in improving its construction and decreasing its cost of manufacture.

10 In carrying out my invention in one form thereof, I provide a bracket for the support of the armature, the bracket extending below the armature and in parallel relation therewith so as to minimize the strains on the bracket incident to the adjustment of the armature. I further provide means for holding the operating coil of the relay on the magnet frame by cupping somewhat an outer lamination of the center pole of

15 the magnetic frame.

20 For a more complete understanding of my invention, reference should now be had to the accompanying drawing wherein I have shown in Fig. 1 a plan view of a relay embodying my invention; Fig. 2 is a sectional elevation taken on the lines 2—2 of Fig. 1; Fig. 3 is a perspective view of the relay mechanism removed from the supporting base; Fig. 4 is a perspective view of the supporting bracket provided for the movable armature, while Fig. 5 is a perspective view of the magnet frame.

25 Referring now to the drawing, I have shown my invention in one form as applied to a relay 10 mounted on an insulating base 11. The relay 30 comprises a three pole or E-shaped magnetic frame 12 provided with an operating coil 14 around the center pole 15 and an armature or single turn coil 18 supported by a spring member 30 and a bracket or cantilever support 20 wider at its lower end than at its upper end. The center pole 15 is provided with extensions 15a and 15b which form in conjunction with extensions 21a and 21b, provided respectively on the outer poles 21 and 22 of the magnetic frame, 35 restricted air gaps 24 and 25. The armature 18 has an opening at one end slightly larger than the center pole 15, the walls of the opening forming a short-circuited coil. The single turn armature coil 18 is provided with two legs 26 and 28 40 to which are secured a spring 30 provided with

a slot 31 and an extension 32 which supports a movable contact 33. A cooperating stationary contact 34 is supported on a bracket 38 secured to the insulating base 11. The spring 30 is secured to one end 40 of the bracket 20 by means of a plate 41 secured to the bracket by means of rivets 43. The opposite end 46 of the bracket 20 is secured to the magnetic frame 12 by means of bolts extending through the holes 47 and 48, the bolts (not shown) being arranged to screw 10 into threaded holes provided in the magnet frame 12.

45 The normal and deenergized position of the armature 18 is adjacent the upper side of the coil 14 and substantially below the restricted air gaps 24 and 25. When a sufficient value of alternating current flows through the operating coil 14 an induced current flows in the single turn coil 18. The interaction between the magnetic fields produced by the single turn coil and the operating coil causes the armature to be moved by a repulsion force upwardly to a point where a pair of magnetizable plates 50 and 51 form a low reluctance path between the restricted air gaps. The armature therefore in moving from a 50 high reluctance path to a low reluctance path operates the movable contact 33 into engagement with the stationary contact 34. The magnetic attractive forces exerted on the magnetizable plates 50 and 51 for a given coil current 30 vary as the square of their distance from the restricted air gaps 24 and 25. Consequently even a slow increase in magnitude of coil current will cause a sudden movement or a snap action of the armature into the picked-up or closed circuit position. With a slow decrease in coil current a similar snap action of the armature from the closed to the open circuit position is obtained.

55 In order to adjust the relay so that it will operate with different values of current flowing 40 through the operating coil, an elongated slot 54 is provided in the end 40 of the bracket 20, which slot provides a relatively small amount of material between the center portion of the bracket and the outer end portion 40. Consequently, 45 by using a pair of pliers or some similar tool the end portion 40 can be readily bent to predetermine the position and spring tension on the armature 18 with respect to the restricted air gaps 24 and 25. A substantial amount of force 50 must be exerted in bending the end 40 of the bracket 20 and to resist this force, to locate the point of bending and to minimize the tendency to loosen the bracket or cantilever support 20 55 from the base, a channel is formed in the central

portion of the bracket and forms on the opposite side of the bracket a ridge 56. It will further be observed that the end portion 46 of the bracket 20 has a much larger cross-sectional area than 5 the end portion 40, the larger cross-sectional area providing additional strength for the lower end of the bracket. All of the bending accomplished by the application of the force to the end 40 of the bracket is therefore limited to the portion 10 of the bracket adjacent the slot 54. Furthermore, the bracket 20 is located in the same vertical plane as the armature 18 with its end 46 secured below the frame 12.

Referring to Fig. 5, it will be observed that 15 the center pole 15 of the laminated magnetic frame 12 has one of its laminations 57 provided with serrations in the form of a pair of outwardly flaring cup-shaped portions 58 and 59, the cup-shaped portions being formed adjacent the lower end of the center pole 15. These cup-shaped or outwardly extending portions cooperate with an insulating spool 60 upon which the turns of the coil 14 are wound. The dimensions of the spool are such that when the coil 14 is placed 20 over the center pole 15 and is pressed downwardly thereon, the cup-shaped portions 58 and 59 are forced into intimate engagement with the inner wall of the spool. Preferably the spool 60 is formed of fiber so that when the fiber spool 25 is pressed on the cup-shaped portions the outer edge of each cup-shaped portion cuts a groove 30 into the fiber thereby preventing turning of the coil or any vibratory movement thereof.

The relay 10, as I have stated, is mounted on 35 the base 11 and as shown in Fig. 2 a cover 62 is arranged to completely enclose the relay. A single screw 63 positively holds the cover in place by reason of the fact that on one side of the cover an inwardly extending nub 65 is provided which cooperates with a depression 66 moulded in the insulating base 11. In placing 40 the cover in position on the base 11, the nub 65 is first placed in the depression 66 and the cover swung to the position shown in Fig. 2. The screw 45 63 extending through a hole in the cover is then screwed into the base 11.

While I have shown a particular embodiment 50 of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by 55 Letters Patent of the United States is:

1. In combination, a repulsion relay provided with a stationary magnetic frame, an exciting coil for said frame, an armature, and means for supporting said armature in cooperative relation with said magnetic frame comprising a cantilever support extending from said magnetic frame in the same vertical plane as said armature to a position in the same horizontal plane as said armature.

2. In combination, a repulsion relay provided with a stationary magnetic frame, an exciting coil for said frame, an armature provided with a short-circuited coil, means for supporting said armature in cooperative relation with said magnetic frame comprising a cantilever support extending from a position adjacent said magnetic frame along the same vertical plane as said armature, and resilient means for securing said armature to the end of said cantilever support remote 75 from said frame.

3. In combination, a repulsion relay provided with a stationary magnetic frame, an exciting coil for said frame, an armature provided with a short-circuited coil, means for supporting said armature in cooperative relation with said magnetic frame comprising a cantilever support extending from a position adjacent said magnetic frame and in the same vertical plane as said armature, and resilient means for securing said armature to the end of said cantilever support remote from said frame, said end of said cantilever support being provided with a slot for permitting and localizing the bending of said end of said support whereby said armature can be adjusted with respect to said magnetic frame. 15

4. In combination, a repulsion relay provided with a stationary magnetic frame, an exciting coil for said frame, an armature provided with a short-circuited coil, means for supporting said armature in cooperative relation with said magnetic frame comprising a cantilever support extending from a position adjacent to and below said magnetic frame and in the same vertical plane as said armature, and resilient means for securing said armature to the upper end of said cantilever support, said cantilever support being provided with a ridge extending substantially from the end of said bar adjacent said magnetic frame to substantially said upper end of said support, said upper end of said support being provided with a transverse slot whereby said upper end of said support can be bent to any desired position, said support being wider at the lower end than at the upper end. 20

5. An alternating current repulsion relay comprising a stationary magnetic frame, an armature provided with a short-circuited coil, a cantilever support for said armature having one end secured adjacent said magnetic frame and the opposite end extending upwardly in the same vertical plane 40 as said armature occupies, an exciting coil for said relay, and means for securing said relay on said frame comprising a pair of cup-shaped portions formed on said frame, the inner portion of said coil being arranged to cooperate with said 45 cup-shaped portions to lock the same in place. 35

6. An alternating current repulsion relay comprising a stationary magnetic frame, an armature provided with a short-circuited coil, a cantilever support for said armature having one end secured adjacent said magnetic frame and the opposite end extending upwardly in the same vertical plane as said armature occupies, an exciting coil for said relay having an insulated support, said magnet being provided with serrations extending 50 slightly beyond the inner walls of said support so that when said coil is forced over said serrations it is locked firmly in place by the deformation of said support by said serrations. 55

7. An alternating current repulsion relay provided with a laminated magnetic frame, one of said laminations being provided with outwardly extending portions, an operating coil for said relay provided with a spool of insulating material, the inner dimensions of said spool being slightly 60 less than the dimensions of said frame whereby said outwardly extending portions are arranged to be pressed into intimate engagement with said spool to lock said coil on said frame. 65

8. An alternating current repulsion relay, a laminated magnetic frame therefor provided with three poles, a pair of cup-shaped portions provided in one of the outer laminations of the middle pole of said frame and adjacent the base of said frame, an operating coil for said relay being 70 75

wound about a spool of insulating material the inner circumference of said spool being less than the circumference of said middle pole at the position occupied by said cup-shaped portions so that when said coil is pressed onto said middle pole said cup-shaped portions are forced into the inner walls of said spool to lock securely said spool on said magnet.

9. An alternating current relay, a laminated

magnetic frame therefor provided with poles, an operating coil for said relay provided with a spool of insulating material surrounding one of said poles, said one of said poles being provided with an outwardly extending portion arranged to engage said spool to lock said coil on said pole when said coil and spool are pressed onto said pole.
